SHUTTLE CHECKING MEANS

Carl D. Brown, Hopedale, Mass., assignor to
Draper Corporation, Hopedale, Mass., a corpora-
tion of Maine

Application November 30, 1942, Serial No. 467,332

4 Claims. (Cl. 139—185)

The present invention relates generally to shuttle boxes for fly shuttle looms and, as illustrated herein, relates more particularly to shuttle checking devices therefor.

In fly shuttle looms, the shuttle is picked into and out of a shuttle box at the end of the lay and the shuttle box is provided with means for stopping or checking the shuttle when the latter enters the shuttle box. In such looms, the shuttle box includes spaced box plates or walls and the shuttle checking means has usually consisted of a binder which is pivotally mounted in one wall of the shuttle box and which checks the shuttle by frictional engagement with the side thereof. The final stopping position of the shuttle was ordinarily determined by engagement of the shuttle with the picker.

The prior construction referred to above has been reasonably satisfactory when used in looms operating at moderate speeds but has not been satisfactory when used in modern high speed looms where high shuttle speeds are necessary. In such high speed looms, it has been necessary to increase the spring pressure on the binder to insure that the shuttle would be properly boxed and also to frequently and accurately adjust the parts. As a result of the increased spring pressure on the binder, the friction on the shuttle and the shuttle box walls caused abnormal wear on these parts.

One object of the present invention, accordingly, is to provide a loom shuttle box having front and back box plates and a binder which is arranged for movement both laterally and longitudinally of the shuttle box to check the shuttle at high speeds. As illustrated, the present binder is provided with a pin and slot connection which causes the binder to move longitudinally of the shuttle box in a direction opposed to the direction of movement of the incoming shuttle thus effectively checking the shuttle without the use of high spring pressure on the binder.

A further object of the invention is to provide a shuttle box with a floating back binder wherein a pin and slot connection between the binder and shuttle box is so arranged that lateral movement of the binder by the shuttle will cause longitudinal movement of the binder in a direction opposed to the direction of movement of the shuttle thus causing increased drag on the shuttle as it approaches its proper stopped position.

With the above and other objects and features in view, the invention will now be described with particular reference to the accompanying draw-

ing which illustrates a preferred embodiment of the invention and in which:

Fig. 1 is a plan view of a shuttle box illustrating a preferred embodiment of the present invention; and

Fig. 2 is a view similar to Fig. 1 but showing the position of the parts when the shuttle is entering the shuttle box.

The drawing shows only a portion of a loom having the invention applied thereto. The parts of the loom which are not shown are of usual construction but it is to be understood, however, that another similar shuttle box is to be applied to the other side of the loom.

15 The drawing illustrates a left hand shuttle box which is mounted on the left hand end of a lay beam 10. The lay beam 10 is mounted on lay swords (not shown) for reciprocation forwardly and rearwardly of the loom. A shuttle 12 is picked along the lay in the usual manner by suitable picking means such, for example, as a picker stick 14 having the usual picker 16 fixed to its upper end.

20 The lay is provided with a shuttle box comprising a front box plate 18 and a back box plate 20. The bottom of the shuttle box is formed by the usual metal lay end 22 which is fixed to the top of the lay 10. The front box plate 18 is adjustably secured to the lay end 22 by bolts 24, 24 which extend through slots 26, 26 formed in the front box plate. A usual leather lining 28 is provided on the inner face of the front box plate to form a suitable friction surface.

25 The back box plate 20 may include a part secured to the lay sword (not shown). This part includes a substantially vertical shuttle engaging and guiding surface 30 and a top plate 32. As illustrated, a part 34 is connected to the first mentioned part of the back box plate and the outer end is fastened to the lay end in the usual manner by a bolt 36. The shuttle engaging surfaces 28, 30 of the shuttle box are spaced apart a distance slightly greater than the width of the shuttle.

30 40 45 The shuttle box is provided with a binder 38 which is arranged to be engaged by and moved by the shuttle as it enters the shuttle box. The binder 38 is provided with a usual friction facing 39 formed of leather. The binder 38 is provided with a rearwardly and inwardly extending slot 40 through which the bolt 36 passes and is maintained thereby in position between the part 34 of the back box plate and the metal lay end 22. Thus, the binder 38 is movable not only laterally but also longitudinally of the lay and because of

the inward inclination of the slot 40, the binder moves rearwardly and also longitudinally of the lay in a direction opposed to the direction of movement of the incoming shuttle. This floating movement of the binder may be obtained in any desired manner but, as above described, is obtained through the rearwardly and inwardly inclined slot 40 and the bolt 36 on which the binder may both pivot and slide laterally of the shuttle box.

A conventional binder spring 42 is provided for yieldingly opposing movement of the inner end of the binder by the incoming shuttle 12. The spring 42 is flat and has its outer end fixed to the lay and its inner end bearing against the inner end of the binder. Pivotal movement of the binder 38 by the incoming shuttle 12 is effective to operate the loom protection mechanism of which only the finger 44 is shown.

Lateral or rearward movement of the binder 38 is yieldingly resisted by a spring plunger 46 which has an enlarged head 47 bearing against the outer end portion of the binder 38. The plunger 46 is slidably mounted in a bracket 48 which is fixed to the rear face of the lay end by cap screws 50. A compression spring 52 is located between the head 47 of the plunger and the bracket 48 and surrounds the shank of the plunger 46. The plunger 46, under the influence of the spring 52, normally urges the outer end of the binder 38 into the position shown in Fig. 2 so that the rear end of the inclined slot 40 bears against the bolt 36 and acts as a stop to limit forward movement of the binder.

When the incoming shuttle 12 engages the inner inclined friction surface 39 of the binder 38, the binder swings rearwardly about the bolt 36 as a pivot and moves the protector finger 44 to operate the protector mechanism. As the incoming shuttle 12 moves outwardly in the shuttle box, the binder 38 is moved rearwardly by the shuttle into the position shown in Fig. 1. Because of the inclination of the slot 40, the binder 38 must also move inwardly in a direction opposed to the direction of movement of the incoming shuttle. Thus while rearward movement of the binder 38 is resisted to some extent by the spring plunger 46, the incoming shuttle 12 resists to a substantially greater extent the longitudinal movement of the binder 38. Checking of the shuttle 12, therefore, is accomplished without applying substantial spring pressure to the binder and picking of the shuttle 12 out of the shuttle box may be accomplished with substantially less power that is necessary where heavy spring pressure alone is used on the binder to check the shuttle.

Having thus described my invention, what I claim as new and desire to secure by Letters Patent of the United States is:

1. In a fly shuttle loom, a lay having a shuttle box comprising front and back box plates, a binder

forming a part of said back plate and having a surface arranged to be engaged by an incoming shuttle, said binder having a rearwardly and inwardly inclined slot in its outer end portion, and a pin in said slot supported by the lay to permit the binder to swing about said pin as a pivot when the incoming shuttle first engages the binder and to cause the binder to move bodily rearwardly and longitudinally of the shuttle box as the shuttle 10 continues its movement into the shuttle box.

2. In a fly shuttle loom, a lay having a shuttle box comprising front and back box plates and a binder mounted for movement laterally and longitudinally of the shuttle box when engaged by an incoming shuttle, said binder having a rearwardly and inwardly inclined slot in its outer end portion, a pin in said slot supported by the lay, said binder being arranged to move laterally and longitudinally of said shuttle box in a direction 15 opposed to the direction of movement of the incoming shuttle to check the shuttle, and means normally maintaining said binder against movement and yieldable upon engagement of said shuttle with said binder to permit lateral displacement of said binder.

3. In a fly shuttle loom, a lay having a shuttle box comprising front and back box plates and a binder mounted for movement laterally and longitudinally of the shuttle box, said binder having a surface projecting into the path of movement of the shuttle and arranged to be engaged by the incoming shuttle, said binder having a rearwardly and inwardly inclined slot formed in its outer end portion, a pin in said slot supported by said lay, a spring engaging the outer end of said binder and normally maintaining the rear end of said slot against said pin but permitting said binder to move relatively to said pin when the binder is engaged by the incoming shuttle, said pin and slot connection cooperating to cause the binder to move longitudinally in a direction opposed to the direction of movement of the incoming shuttle as the binder is displaced laterally by said shuttle.

4. In a fly shuttle loom, a lay having a shuttle 45 box, comprising front and back box plates and a movable binder, said binder having a surface arranged for engagement with the incoming shuttle and arranged to be moved laterally thereby, said binder having a slot in its outer end portion, inclined rearwardly and inwardly of the shuttle box, a pin in said slot supported by said lay, said pin and slot connection causing the binder to move longitudinally of the shuttle box in a direction opposed to the direction of movement of the incoming shuttle as the binder is displaced laterally by the incoming shuttle, and means for resiliently maintaining said binder with its shuttle engaging surface projecting into the path of movement of the incoming shuttle and to resist lateral displacement of said binder by the incoming shuttle.

CARL D. BROWN.
